ABSTRACT

A game table for games in which a ball is bounced on a table surface, wherein the table is formed of two surfaces separated from each other to provide a surface level open space therebetween, with a barrier having an opening therein between said separate surfaces.

**GAME TABLE WITH CENTRALLY DISPOSED
APERTURED BARRIER**

This is a continuation-in-part of patent application Ser. No. 827,418, filed May 23, 1969.

BACKGROUND OF THE INVENTION

This invention relates in general to a game table with an intermediate barrier having an opening therein, and more particularly to a game table having two spaced apart playing surfaces.

As is perhaps well-known, table tennis is a variety of the game of tennis which is played on a table with small paddles and a small hollow celluloid or plastic ball. The table is divided into two sections, one for each player or team of players. A net separates each section or playing surface. In playing the game, the ball is knocked back and forth over the net by the players. The net serves as a hazard to be avoided by the travelling ball.

BRIEF DESCRIPTION OF THE INVENTION

The present invention relates to a new and improved gaming table including two spaced apart playing surfaces with a barrier extending transversely across the open space between each playing surface. The barrier has an opening therein. The ball must pass through the opening in the barrier.

It is an object of this invention to provide a gaming table having an intermediate barrier with an opening therein.

A further object of this invention is to provide a gaming table having spaced apart gaming surfaces and an intermediate barrier with an opening therein.

In accordance with these and other objects which will be apparent hereinafter, the instant invention will now be described with particular reference to the accompanying drawing.

BRIEF DESCRIPTION OF THE DRAWING

In the drawing:

FIG. 1 is a top plan view of a game table,
FIG. 2 is a side elevation view of the game table, and
FIG. 3 is a front view of the barrier.

DESCRIPTION OF A PREFERRED EMBODIMENT

Referring now to FIG. 1, the game table includes two sections 5 and 6. Section 5 has a relatively flat upper playing surface 7 and supporting members 8. Section 6 has a relatively flat upper playing surface 9 and supporting members 10. A barrier 11 is supported by arms 12, 13, 14, and 15. The arms 12, 13, 14, and 15 are connected to sections 5 and 6 respec-

tively. Although the supporting members 8 and 10, as shown in FIG. 2, are ordinary legs, any suitable type of supports may be utilized. For example, folding legs could be provided to make a portable gaming table.

5 The sections 5 and 6 are fastened together by means of connecting arms 12, 13, 14, and 15 fastened to holding bars 16 and 17 respectively. The holding bars sandwich the bottom portion 18 of barrier 11 therebetween.

Surfaces 7 and 9 are illustrated as being substantially pie shaped with the smaller ends of the sections facing each other. To provide a larger space between the two sections 5 and 6, the corners of the two sections are rounded off in the manner illustrated in FIG. 1. The outer surfaces are also rounded so as to remove any sharp corners which might become hazardous to the players.

The side or vertical edges of tables 5 and 6 are tapered to provide a very thin edge in order that the chances that the playing ball would engage the edges are substantially reduced.

The instant invention has been shown and described herein 20 in what is considered to be the most practical and preferred embodiment. It is recognized, however, that departures may be made therefrom within the scope of the invention and that obvious modifications will occur to a person skilled in the art.

What is claimed is:

25 1. A game table for moving a Ping-Pong ball from one surface to another comprising:

a first table with a first horizontal playing surface, and a second table with a second horizontal playing surface, each table having legs supporting said horizontal playing surfaces in the same plane, a vertical barrier disposed centrally between said horizontal surfaces and extending transversely therebetween, said barrier having an opening therein of a size substantially larger than a conventional Ping-Pong ball, connection means secured underneath the adjoining edges of said horizontal surfaces connecting the tables in spaced relationship, said barrier being attached to said connecting means below and adjacent said adjoining edges.

2. A game table for moving a ball from one surface to 40 another as set forth in claim 1 wherein, said barrier has a longitudinal length greater than the width of the gaming table.

3. A game table for moving a ball from one surface to another as set forth in claim 2 wherein, 45 said barrier projects upward above the plane of the playing surface.
